United States Patent

Des. 234,281
Patented Feb. 11, 1975

234,281

CHAIR

Akihiko Noda and Akira Hirose, Tokyo, Japan, assignors
to France Bed Co., Ltd., Tokyo, Japan

Filed Feb. 28, 1973, Ser. No. 336,528

Term of patent 7 years

Int. Cl. D6—01

U.S. Cl. D6—76

FIG. 1 is a top plan view of a chair showing our design;
FIG. 2 is a front elevational view thereof;

FIG. 3 is a bottom plan view thereof;

FIG. 4 is a right side elevational view thereof;

FIG. 5 is a left side elevational view thereof; and

FIG. 6 is a perspective view thereof.

The left side elevational view is a mirror image of FIG. 4 and is omitted.

We claim:

The ornamental design for a chair, as shown and described.
